[57] ABSTRACT

An electrical connector for electrically interconnecting at least one electrical wire and at least one contacting member within an insulative member. The connector includes an insulative housing, at least one contact having a contacting portion positioned within the housing and a tail portion extending from the housing and adapted for electrically contacting said contacting member, and a pivotally mounted cover means pivoted on one end to the housing and adapted for covering a recessed area within said housing. An electrical contact which may be used in the above connector is also disclosed.

ELECTRICAL CONNECTOR AND CONTACT

BACKGROUND OF THE INVENTION

The present invention relates to electrical connectors and more particularly to connectors for electrically interconnecting a first conductive means, e.g. electrical wire, with a second conductive means such as a printed circuit board connector.

Broadly speaking, the invention involves the electrical interconnection of at least one electrical wire with a corresponding contacting member positioned within an insulative member. As stated, an example of this contacting member-insulative member arrangement is a printed circuit board (PCB) connector. Most PCB connectors include a plurality of individual electrical contacts spacedly positioned within an insulative housing adjacent a printed circuit board receiving slot. When the board is inserted within the slot, the contacts normally engage designated conductive paths on the board. Because the tail portions of the contacts are electrically joined to an external conductive means, e.g. electrical wiring, the PCB connector serves as an interconnection between the board and wiring.

As will be described, the connector of the present invention is adapted for being positioned within and electrically contacting a contacting member-insulative member component such as a PCB connector. The connector of the invention is also adapted for securing and electrically contacting at least one electrical wire. Accordingly, the invention provides a means for electrically interconnecting the wire with the contacting member positioned within said insulative member. In the particular case of PCB connectors wherein the connector's contact tail portions are joined to electrical wiring, the present invention assures a unique means for electrically joining a first plurality of wires with the second plurality of wires joined to said tail portions. This interconnection is achieved without the necessity of several relatively complex wiring operations heretofore required in the prior art.

It is therefore believed that an electrical connector capable of interconnecting at least one electrical wire with at least one contacting member positioned within an insulative housing, e.g. a PCB connector, would constitute a significant advancement in the art. It is further believed that a new electrical contact, capable of being utilized within the connector as defined above, would also constitute an advancement in the art.

OBJECTS AND SUMMARY OF THE INVENTION

It is a primary object of the invention to enhance the electrical connector art.

It is another object of the present invention to provide an electrical connector adapted for electrically interconnecting at least one electrical wire with at least one contacting member located within an insulative member, an example of such a contacting member-insulative member assembly being a typical printed circuit board connector.

It is still another object of the invention to provide an electrical contact which may be used in the above connector.

In accordance with one aspect of the invention there is provided an electrical connector for electrically interconnecting at least one electrical wire and at least one

electrical contacting member positioned within an insulative member. The connector comprises an electrically insulative housing comprising a body portion and at least one contact receiving portion, and an extending portion extending from the body portion, at least one electrical contact including a contacting portion, a retention portion, and a tail portion, and a cover means including first and second opposing end portions, one of said end portions pivotally mounted on the housing.

In accordance with another aspect of the invention there is provided an electrical contact for contacting an electrical wire having a substantially round conductive portion, said contact comprising a contacting portion including a base portion and first and second opposingly positioned and substantially upstanding sides, each of the sides having an opening therein. The width of the slotted opening within the first side is substantially uniform and equal to or less than the diameter of the wire's conductive portion. The opening within the second side includes a substantially V-shaped angular edge portion, the depth of said edge portion less than the depth of said slotted opening. The contact further comprises a retention portion substantially adjacent said contacting portion, and a tail portion substantially adjacent the retention portion.

BRIEF DESCRIPTION OF THE DRAWINGS

FIG. 1 is an isometric view of a preferred embodiment of the connector of the invention;

FIG. 2 is an isometric view of the housing of the connector of FIG. 1;

FIG. 3 is an enlarged side view illustrating the positioning relationship of the preferred contact of the invention within the housing of FIG. 2;

FIG. 4 is an isometric view of one embodiment of a cover means for the invention;

FIG. 5 is an isometric view of a preferred embodiment for the contact of the invention;

FIG. 5A is an end view taken along the line 5A—5A in FIG. 5;

FIG. 6 is an end elevational view of the connector of FIG. 1;

FIG. 7 is an enlarged end elevational view of the pivotal arrangement of the cover means and housing of the connector of FIG. 1;

FIG. 8 is an enlarged isometric view of an alternate embodiment of a cover means for the invention; and

FIGS. 9 and 10 represent a sequence of operation for severing an electrical wire within the contact of the invention using the cover means of FIG. 8.

DETAILED DESCRIPTION OF THE PREFERRED EMBODIMENTS

For a better understanding of the present invention, together with other and further objects, advantages and capabilities thereof, reference is made to the following disclosure and appended claims in connection with the above-described drawings.

With reference to FIG. 1, there is shown an electrical connector 10 in accordance with a preferred embodiment of the invention. Connector 10 is adapted for electrically interconnecting at least one electrical wire 11 with at least one electrical contacting member 13 positioned within an insulative member 15, a typical example of such a contacting member-insulative member assembly being a printed circuit board (PCB) connector 17. As will be described, connector 10 is adapted

for receiving a printed circuit board 19 within the housing 15. The housing 15 includes a base 21 and a cover 23. The base 21 includes a slot 25 for receiving the printed circuit board 19. The cover 23 is pivotally mounted on the base 21. The cover 23 includes a base portion 27 and a cover portion 29. The base portion 27 is pivotally mounted on the base 21. The cover portion 29 is pivotally mounted on the base portion 27. The cover portion 29 includes a base 31 and a cover 33. The base 31 is pivotally mounted on the base portion 27. The cover 33 is pivotally mounted on the base 31. The cover 33 includes a base 35 and a cover 37. The base 35 is pivotally mounted on the base 31. The cover 37 is pivotally mounted on the base 35. The cover 37 includes a base 39 and a cover 41. The base 39 is pivotally mounted on the base 35. The cover 41 is pivotally mounted on the base 39. The cover 41 includes a base 43 and a cover 45. The base 43 is pivotally mounted on the base 39. The cover 45 is pivotally mounted on the base 43. The cover 45 includes a base 47 and a cover 49. The base 47 is pivotally mounted on the base 43. The cover 49 is pivotally mounted on the base 47. The cover 49 includes a base 51 and a cover 53. The base 51 is pivotally mounted on the base 47. The cover 53 is pivotally mounted on the base 51. The cover 53 includes a base 55 and a cover 57. The base 55 is pivotally mounted on the base 51. The cover 57 is pivotally mounted on the base 55. The cover 57 includes a base 59 and a cover 61. The base 59 is pivotally mounted on the base 55. The cover 61 is pivotally mounted on the base 59. The cover 61 includes a base 63 and a cover 65. The base 63 is pivotally mounted on the base 59. The cover 65 is pivotally mounted on the base 63. The cover 65 includes a base 67 and a cover 69. The base 67 is pivotally mounted on the base 63. The cover 69 is pivotally mounted on the base 67. The cover 69 includes a base 71 and a cover 73. The base 71 is pivotally mounted on the base 67. The cover 73 is pivotally mounted on the base 71. The cover 73 includes a base 75 and a cover 77. The base 75 is pivotally mounted on the base 71. The cover 77 is pivotally mounted on the base 75. The cover 77 includes a base 79 and a cover 81. The base 79 is pivotally mounted on the base 75. The cover 81 is pivotally mounted on the base 79. The cover 81 includes a base 83 and a cover 85. The base 83 is pivotally mounted on the base 79. The cover 85 is pivotally mounted on the base 83. The cover 85 includes a base 87 and a cover 89. The base 87 is pivotally mounted on the base 83. The cover 89 is pivotally mounted on the base 87. The cover 89 includes a base 91 and a cover 93. The base 91 is pivotally mounted on the base 87. The cover 93 is pivotally mounted on the base 91. The cover 93 includes a base 95 and a cover 97. The base 95 is pivotally mounted on the base 91. The cover 97 is pivotally mounted on the base 95. The cover 97 includes a base 99 and a cover 101. The base 99 is pivotally mounted on the base 95. The cover 101 is pivotally mounted on the base 99. The cover 101 includes a base 103 and a cover 105. The base 103 is pivotally mounted on the base 99. The cover 105 is pivotally mounted on the base 103. The cover 105 includes a base 107 and a cover 109. The base 107 is pivotally mounted on the base 103. The cover 109 is pivotally mounted on the base 107. The cover 109 includes a base 111 and a cover 113. The base 111 is pivotally mounted on the base 107. The cover 113 is pivotally mounted on the base 111. The cover 113 includes a base 115 and a cover 117. The base 115 is pivotally mounted on the base 111. The cover 117 is pivotally mounted on the base 115. The cover 117 includes a base 119 and a cover 121. The base 119 is pivotally mounted on the base 115. The cover 121 is pivotally mounted on the base 119. The cover 121 includes a base 123 and a cover 125. The base 123 is pivotally mounted on the base 119. The cover 125 is pivotally mounted on the base 123. The cover 125 includes a base 127 and a cover 129. The base 127 is pivotally mounted on the base 123. The cover 129 is pivotally mounted on the base 127. The cover 129 includes a base 131 and a cover 133. The base 131 is pivotally mounted on the base 127. The cover 133 is pivotally mounted on the base 131. The cover 133 includes a base 135 and a cover 137. The base 135 is pivotally mounted on the base 131. The cover 137 is pivotally mounted on the base 135. The cover 137 includes a base 139 and a cover 141. The base 139 is pivotally mounted on the base 135. The cover 141 is pivotally mounted on the base 139. The cover 141 includes a base 143 and a cover 145. The base 143 is pivotally mounted on the base 139. The cover 145 is pivotally mounted on the base 143. The cover 145 includes a base 147 and a cover 149. The base 147 is pivotally mounted on the base 143. The cover 149 is pivotally mounted on the base 147. The cover 149 includes a base 151 and a cover 153. The base 151 is pivotally mounted on the base 147. The cover 153 is pivotally mounted on the base 151. The cover 153 includes a base 155 and a cover 157. The base 155 is pivotally mounted on the base 151. The cover 157 is pivotally mounted on the base 155. The cover 157 includes a base 159 and a cover 161. The base 159 is pivotally mounted on the base 155. The cover 161 is pivotally mounted on the base 159. The cover 161 includes a base 163 and a cover 165. The base 163 is pivotally mounted on the base 159. The cover 165 is pivotally mounted on the base 163. The cover 165 includes a base 167 and a cover 169. The base 167 is pivotally mounted on the base 163. The cover 169 is pivotally mounted on the base 167. The cover 169 includes a base 171 and a cover 173. The base 171 is pivotally mounted on the base 167. The cover 173 is pivotally mounted on the base 171. The cover 173 includes a base 175 and a cover 177. The base 175 is pivotally mounted on the base 171. The cover 177 is pivotally mounted on the base 175. The cover 177 includes a base 179 and a cover 181. The base 179 is pivotally mounted on the base 175. The cover 181 is pivotally mounted on the base 179. The cover 181 includes a base 183 and a cover 185. The base 183 is pivotally mounted on the base 179. The cover 185 is pivotally mounted on the base 183. The cover 185 includes a base 187 and a cover 189. The base 187 is pivotally mounted on the base 183. The cover 189 is pivotally mounted on the base 187. The cover 189 includes a base 191 and a cover 193. The base 191 is pivotally mounted on the base 187. The cover 193 is pivotally mounted on the base 191. The cover 193 includes a base 195 and a cover 197. The base 195 is pivotally mounted on the base 191. The cover 197 is pivotally mounted on the base 195. The cover 197 includes a base 199 and a cover 201. The base 199 is pivotally mounted on the base 195. The cover 201 is pivotally mounted on the base 199. The cover 201 includes a base 203 and a cover 205. The base 203 is pivotally mounted on the base 199. The cover 205 is pivotally mounted on the base 203. The cover 205 includes a base 207 and a cover 209. The base 207 is pivotally mounted on the base 203. The cover 209 is pivotally mounted on the base 207. The cover 209 includes a base 211 and a cover 213. The base 211 is pivotally mounted on the base 207. The cover 213 is pivotally mounted on the base 211. The cover 213 includes a base 215 and a cover 217. The base 215 is pivotally mounted on the base 211. The cover 217 is pivotally mounted on the base 215. The cover 217 includes a base 219 and a cover 221. The base 219 is pivotally mounted on the base 215. The cover 221 is pivotally mounted on the base 219. The cover 221 includes a base 223 and a cover 225. The base 223 is pivotally mounted on the base 219. The cover 225 is pivotally mounted on the base 223. The cover 225 includes a base 227 and a cover 229. The base 227 is pivotally mounted on the base 223. The cover 229 is pivotally mounted on the base 227. The cover 229 includes a base 231 and a cover 233. The base 231 is pivotally mounted on the base 227. The cover 233 is pivotally mounted on the base 231. The cover 233 includes a base 235 and a cover 237. The base 235 is pivotally mounted on the base 231. The cover 237 is pivotally mounted on the base 235. The cover 237 includes a base 239 and a cover 241. The base 239 is pivotally mounted on the base 235. The cover 241 is pivotally mounted on the base 239. The cover 241 includes a base 243 and a cover 245. The base 243 is pivotally mounted on the base 239. The cover 245 is pivotally mounted on the base 243. The cover 245 includes a base 247 and a cover 249. The base 247 is pivotally mounted on the base 243. The cover 249 is pivotally mounted on the base 247. The cover 249 includes a base 251 and a cover 253. The base 251 is pivotally mounted on the base 247. The cover 253 is pivotally mounted on the base 251. The cover 253 includes a base 255 and a cover 257. The base 255 is pivotally mounted on the base 251. The cover 257 is pivotally mounted on the base 255. The cover 257 includes a base 259 and a cover 261. The base 259 is pivotally mounted on the base 255. The cover 261 is pivotally mounted on the base 259. The cover 261 includes a base 263 and a cover 265. The base 263 is pivotally mounted on the base 259. The cover 265 is pivotally mounted on the base 263. The cover 265 includes a base 267 and a cover 269. The base 267 is pivotally mounted on the base 263. The cover 269 is pivotally mounted on the base 267. The cover 269 includes a base 271 and a cover 273. The base 271 is pivotally mounted on the base 267. The cover 273 is pivotally mounted on the base 271. The cover 273 includes a base 275 and a cover 277. The base 275 is pivotally mounted on the base 271. The cover 277 is pivotally mounted on the base 275. The cover 277 includes a base 279 and a cover 281. The base 279 is pivotally mounted on the base 275. The cover 281 is pivotally mounted on the base 279. The cover 281 includes a base 283 and a cover 285. The base 283 is pivotally mounted on the base 279. The cover 285 is pivotally mounted on the base 283. The cover 285 includes a base 287 and a cover 289. The base 287 is pivotally mounted on the base 283. The cover 289 is pivotally mounted on the base 287. The cover 289 includes a base 291 and a cover 293. The base 291 is pivotally mounted on the base 287. The cover 293 is pivotally mounted on the base 291. The cover 293 includes a base 295 and a cover 297. The base 295 is pivotally mounted on the base 291. The cover 297 is pivotally mounted on the base 295. The cover 297 includes a base 299 and a cover 301. The base 299 is pivotally mounted on the base 295. The cover 301 is pivotally mounted on the base 299. The cover 301 includes a base 303 and a cover 305. The base 303 is pivotally mounted on the base 299. The cover 305 is pivotally mounted on the base 303. The cover 305 includes a base 307 and a cover 309. The base 307 is pivotally mounted on the base 303. The cover 309 is pivotally mounted on the base 307. The cover 309 includes a base 311 and a cover 313. The base 311 is pivotally mounted on the base 307. The cover 313 is pivotally mounted on the base 311. The cover 313 includes a base 315 and a cover 317. The base 315 is pivotally mounted on the base 307. The cover 317 is pivotally mounted on the base 315. The cover 317 includes a base 319 and a cover 321. The base 319 is pivotally mounted on the base 307. The cover 321 is pivotally mounted on the base 319. The cover 321 includes a base 323 and a cover 325. The base 323 is pivotally mounted on the base 307. The cover 325 is pivotally mounted on the base 323. The cover 325 includes a base 327 and a cover 329. The base 327 is pivotally mounted on the base 307. The cover 329 is pivotally mounted on the base 327. The cover 329 includes a base 331 and a cover 333. The base 331 is pivotally mounted on the base 307. The cover 333 is pivotally mounted on the base 331. The cover 333 includes a base 335 and a cover 337. The base 335 is pivotally mounted on the base 307. The cover 337 is pivotally mounted on the base 335. The cover 337 includes a base 339 and a cover 341. The base 339 is pivotally mounted on the base 307. The cover 341 is pivotally mounted on the base 339. The cover 341 includes a base 343 and a cover 345. The base 343 is pivotally mounted on the base 307. The cover 345 is pivotally mounted on the base 343. The cover 345 includes a base 347 and a cover 349. The base 347 is pivotally mounted on the base 307. The cover 349 is pivotally mounted on the base 347. The cover 349 includes a base 351 and a cover 353. The base 351 is pivotally mounted on the base 307. The cover 353 is pivotally mounted on the base 351. The cover 353 includes a base 355 and a cover 357. The base 355 is pivotally mounted on the base 307. The cover 357 is pivotally mounted on the base 355. The cover 357 includes a base 359 and a cover 361. The base 359 is pivotally mounted on the base 307. The cover 361 is pivotally mounted on the base 359. The cover 361 includes a base 363 and a cover 365. The base 363 is pivotally mounted on the base 307. The cover 365 is pivotally mounted on the base 363. The cover 365 includes a base 367 and a cover 369. The base 367 is pivotally mounted on the base 307. The cover 369 is pivotally mounted on the base 367. The cover 369 includes a base 371 and a cover 373. The base 371 is pivotally mounted on the base 307. The cover 373 is pivotally mounted on the base 371. The cover 373 includes a base 375 and a cover 377. The base 375 is pivotally mounted on the base 307. The cover 377 is pivotally mounted on the base 375. The cover 377 includes a base 379 and a cover 381. The base 379 is pivotally mounted on the base 307. The cover 381 is pivotally mounted on the base 379. The cover 381 includes a base 383 and a cover 385. The base 383 is pivotally mounted on the base 307. The cover 385 is pivotally mounted on the base 383. The cover 385 includes a base 387 and a cover 389. The base 387 is pivotally mounted on the base 307. The cover 389 is pivotally mounted on the base 387. The cover 389 includes a base 391 and a cover 393. The base 391 is pivotally mounted on the base 307. The cover 393 is pivotally mounted on the base 391. The cover 393 includes a base 395 and a cover 397. The base 395 is pivotally mounted on the base 307. The cover 397 is pivotally mounted on the base 395. The cover 397 includes a base 399 and a cover 401. The base 399 is pivotally mounted on the base 307. The cover 401 is pivotally mounted on the base 399. The cover 401 includes a base 403 and a cover 405. The base 403 is pivotally mounted on the base 307. The cover 405 is pivotally mounted on the base 403. The cover 405 includes a base 407 and a cover 409. The base 407 is pivotally mounted on the base 307. The cover 409 is pivotally mounted on the base 407. The cover 409 includes a base 411 and a cover 413. The base 411 is pivotally mounted on the base 307. The cover 413 is pivotally mounted on the base 411. The cover 413 includes a base 415 and a cover 417. The base 415 is pivotally mounted on the base 307. The cover 417 is pivotally mounted on the base 415. The cover 417 includes a base 419 and a cover 421. The base 419 is pivotally mounted on the base 307. The cover 421 is pivotally mounted on the base 419. The cover 421 includes a base 423 and a cover 425. The base 423 is pivotally mounted on the base 307. The cover 425 is pivotally mounted on the base 423. The cover 425 includes a base 427 and a cover 429. The base 427 is pivotally mounted on the base 307. The cover 429 is pivotally mounted on the base 427. The cover 429 includes a base 431 and a cover 433. The base 431 is pivotally mounted on the base 307. The cover 433 is pivotally mounted on the base 431. The cover 433 includes a base 435 and a cover 437. The base 435 is pivotally mounted on the base 307. The cover 437 is pivotally mounted on the base 435. The cover 437 includes a base 439 and a cover 441. The base 439 is pivotally mounted on the base 307. The cover 441 is pivotally mounted on the base 439. The cover 441 includes a base 443 and a cover 445. The base 443 is pivotally mounted on the base 307. The cover 445 is pivotally mounted on the base 443. The cover 445 includes a base 447 and a cover 449. The base 447 is pivotally mounted on the base 307. The cover 449 is pivotally mounted on the base 447. The cover 449 includes a base 451 and a cover 453. The base 451 is pivotally mounted on the base 307. The cover 453 is pivotally mounted on the base 451. The cover 453 includes a base 455 and a cover 457. The base 455 is pivotally mounted on the base 307. The cover 457 is pivotally mounted on the base 455. The cover 457 includes a base 459 and a cover 461. The base 459 is pivotally mounted on the base 307. The cover 461 is pivotally mounted on the base 459. The cover 461 includes a base 463 and a cover 465. The base 463 is pivotally mounted on the base 307. The cover 465 is pivotally mounted on the base 463. The cover 465 includes a base 467 and a cover 469. The base 467 is pivotally mounted on the base 307. The cover 469 is pivotally mounted on the base 467. The cover 469 includes a base 471 and a cover 473. The base 471 is pivotally mounted on the base 307. The cover 473 is pivotally mounted on the base 471. The cover 473 includes a base 475 and a cover 477. The base 475 is pivotally mounted on the base 307. The cover 477 is pivotally mounted on the base 475. The cover 477 includes a base 479 and a cover 481. The base 479 is pivotally mounted on the base 307. The cover 481 is pivotally mounted on the base 479. The cover 481 includes a base 483 and a cover 485. The base 483 is pivotally mounted on the base 307. The cover 485 is pivotally mounted on the base 483. The cover 485 includes a base 487 and a cover 489. The base 487 is pivotally mounted on the base 307. The cover 489 is pivotally mounted on the base 487. The cover 489 includes a base 491 and a cover 493. The base 491 is pivotally mounted on the base 307. The cover 493 is pivotally mounted on the base 491. The cover 493 includes a base 495 and a cover 497. The base 495 is pivotally mounted on the base 307. The cover 497 is pivotally mounted on the base 495. The cover 497 includes a base 499 and a cover 501. The base 499 is pivotally mounted on the base 307. The cover 501 is pivotally mounted on the base 499. The cover 501 includes a base 503 and a cover 505. The base 503 is pivotally mounted on the base 307. The cover 505 is pivotally mounted on the base 503. The cover 505 includes a base 507 and a cover 509. The base 507 is pivotally mounted on the base 307. The cover 509 is pivotally mounted on the base 507. The cover 509 includes a base 511 and a cover 513. The base 511 is pivotally mounted on the base 307. The cover 513 is pivotally mounted on the base 511. The cover 513 includes a base 515 and a cover 517. The base 515 is pivotally mounted on the base 307. The cover 517 is pivotally mounted on the base 515. The cover 517 includes a base 519 and a cover 521. The base 519 is pivotally mounted on the base 307. The cover 521 is pivotally mounted on the base 519. The cover 521 includes a base 523 and a cover 525. The base 523 is pivotally mounted on the base 307. The cover 525 is pivotally mounted on the base 523. The cover 525 includes a base 527 and a cover 529. The base 527 is pivotally mounted on the base 307. The cover 529 is pivotally mounted on the base 527. The cover 529 includes a base 531 and a cover 533. The base 531 is pivotally mounted on the base 307. The cover 533 is pivotally mounted on the base 531. The cover 533 includes a base 535 and a cover 537. The base 535 is pivotally mounted on the base 307. The cover 537 is pivotally mounted on the base 535. The cover 537 includes a base 539 and a cover 541. The base 539 is pivotally mounted on the base 307. The cover 541 is pivotally mounted on the base 539. The cover 541 includes a base 543 and a cover 545. The base 543 is pivotally mounted on the base 307. The cover 545 is pivotally mounted on the base 543. The cover 545 includes a base 547 and a cover 549. The base 547 is pivotally mounted on the base 307. The cover 549 is pivotally mounted on the base 547. The cover 549 includes a base 551 and a cover 553. The base 551 is pivotally mounted on the base 307. The cover 553 is pivotally mounted on the base 551. The cover 553 includes a base 555 and a cover 557. The base 555 is pivotally mounted on the base 307. The cover 557 is pivotally mounted on the base 555. The cover 557 includes a base 559 and a cover 561. The base 559 is pivotally mounted on the base 307. The cover 561 is pivotally mounted on the base 559. The cover 561 includes a base 563 and a cover 565. The base 563 is pivotally mounted on the base 307. The cover 565 is pivotally mounted on the base 563. The cover 565 includes a base 567 and a cover 569. The base 567 is pivotally mounted on the base 307. The cover 569 is pivotally mounted on the base 567. The cover 569 includes a base 571 and a cover 573. The base 571 is pivotally mounted on the base 307. The cover 573 is pivotally mounted on the base 571. The cover 573 includes a base 575 and a cover 577. The base 575 is pivotally mounted on the base 307. The cover 577 is pivotally mounted on the base 575. The cover 577 includes a base 579 and a cover 581. The base 579 is pivotally mounted on the base 307. The cover 581 is pivotally mounted on the base 579. The cover 581 includes a base 583 and a cover 585. The base 583 is pivotally mounted on the base 307. The cover 585 is pivotally mounted on the base 583. The cover 585 includes a base 587 and a cover 589. The base 587 is pivotally mounted on the base 307. The cover 589 is pivotally mounted on the base 587. The cover 589 includes a base 591 and a cover 593. The base 591 is pivotally mounted on the base 307. The cover 593 is pivotally mounted on the base 591. The cover 593 includes a base 595 and a cover 597. The base 595 is pivotally mounted on the base 307. The cover 597 is pivotally mounted on the base 595. The cover 597 includes a base 599 and a cover 601. The base 599 is pivotally mounted on the base 307. The cover 601 is pivotally mounted on the base 599. The cover 601 includes a base 603 and a cover 605. The base 603 is pivotally mounted on the base 307. The cover 605 is pivotally mounted on the base 603. The cover 605 includes a base 607 and a cover 609. The base 607 is pivotally mounted on the base 307. The cover 609 is pivotally mounted on the base 607. The cover 609 includes a base 611 and a cover 613. The base 611 is pivotally mounted on the base 307. The cover 613 is pivotally mounted on the base 611. The cover 613 includes a base 615 and a cover 617. The base 615 is pivotally mounted on the base 307. The cover 617 is pivotally mounted on the base 615. The cover 617 includes a base 619 and a cover 621. The base 619 is pivotally mounted on the base 307. The cover 621 is pivotally mounted on the base 619. The cover 621 includes a base 623 and a cover 625. The base 623 is pivotally mounted on the base 307. The cover 625 is pivotally mounted on the base 623. The cover 625 includes a base 627 and a cover 629. The base 627 is pivotally mounted on the base 307. The cover 629 is pivotally mounted on the base 627. The cover 629 includes a base 631 and a cover 633. The base 631 is pivotally mounted on the base 307. The cover 633 is pivotally mounted on the base 631. The cover 633 includes a base 635 and a cover 637. The base 635 is pivotally mounted on the base 307. The cover 637 is pivotally mounted on the base 635. The cover 637 includes a base 639 and a cover 641. The base 639 is pivotally mounted on the base 307. The cover 641 is pivotally mounted on the base 639. The cover 641 includes a base 643 and a cover 645. The base 643 is pivotally mounted on the base 307. The cover 645 is pivotally mounted on the base 643. The cover 645 includes a base 647 and a cover 649. The base 647 is pivotally mounted on the base 307. The cover 649 is pivotally mounted on the base 647. The cover 649 includes a base 651 and a cover 653. The base 651 is pivotally mounted on the base 307. The cover 653 is pivotally mounted on the base 651. The cover 653 includes a base 655 and a cover 657. The base 655 is pivotally mounted on the base 307. The cover 657 is pivotally mounted on the base 655. The cover 657 includes a base 659 and a cover 661. The base 659 is pivotally mounted on the base 307. The cover 661 is pivotally mounted on the base 659. The cover 661 includes a base 663 and a cover 665. The base 663 is pivotally mounted on the base 307. The cover 665 is pivotally mounted on the base 663. The cover 665 includes a base 667 and a cover 669. The base 667 is pivotally mounted on the base 307. The cover 669 is pivotally mounted on the base 667. The cover 669 includes a base 671 and a cover 673. The base 671 is pivotally mounted on the base 307. The cover 673 is pivotally mounted on the base 671. The cover 673 includes a base 675 and a cover 677. The

for being positioned within the PCB connector's board receiving slot 19.

Although the present invention is defined in its broader aspects as connecting aspects as connecting at least one wire 11 with a corresponding contacting member 13, a preferred usage for connector 10 is to electrically interconnect a plurality of electrical wires 11 positioned within a cable 21 or similar sheath member with a corresponding plurality of contacting members 13 spacedly positioned in insulative member 15. As will also be described, connector 10 is capable of connecting contacts 13 positioned in opposingly oriented rows within member 15.

Connector 10 comprises an electrically insulative housing 23, at least one electrical contact 25, and at least one cover means 27. When contacting a plurality of wires 11 to a PCB connector 17 having a plurality of contacting members, it is understood that connector 10 includes a corresponding plurality of contacts 25.

Insulative housing 23 comprises a body portion 29 which includes at least one recessed area 31 therein. In the embodiment shown in FIGS. 1 and 2, body portion 29 includes two such recessed areas. Recessed area 31 is adapted for having wire 11 located therein. When connecting a plurality of wires 11 and incorporating two recessed areas 31, it is shown in FIG. 1 that some of the wires 11 are located within one recessed area 31 while the remaining wires are substantially located within the other area 31 positioned on the opposing side of body portion 29.

Housing 23 also includes at least one contact receiving portion 33 (shown in FIGS. 2 and 3) positioned relative to recessed portion 31. It is understood that housing 23 includes one contact receiving portion 33 for each of the contacts 25 within connector 10. Housing 23 further includes an extending portion 35 extending from body portion 29. As shown in FIG. 6, extending portion 35 is adapted for being positioned within slot 19 of PCB connector 17.

Each of the electrical contacts of connector 10 comprises a contacting portion 37 (FIGS. 2 and 3), a retention portion 39, and a tail portion 41. Reference is also called to FIG. 5 for a more detailed view of contact 25.

Contacting portion 37 is adapted for being positioned within contact receiving portion 33 of housing 23 and is further adapted for having one of the electrical wires 11 positioned therein. As will be described, complete positioning of wire 11 within contacting portion 37 assures electrical contact between the conductive portion of the wire and the contacting portion.

Retention portion 39 of contact 25 is positioned adjacent contacting portions 37 and is adapted for retaining portion 37 within contact receiving portion 33. Tail portion 41 is positioned adjacent retention portion 39 and is adapted for electrically contacting the corresponding contacting member 13 within PCB connector 17 when extending portion 35 of housing 23 is positioned therein. As illustrated in FIG. 6, tail portion 41 extends from body portion 29 of housing 23 in engaged relationship to extending portion 35 of said housing.

Cover means 27 of connector 10 comprises first and second opposing end portions 43 and 45, respectively. Although only one cover means 27 is required in accordance with the broad aspect of the invention, connector 10 preferably comprises two such members. This is preferred when using a housing 23 which includes two recessed areas 31 for housing a plurality of wires 11. Each cover 27 is pivotally mounted within housing 23

in the region substantially adjacent contact receiving portion 33. More specifically, first end portion 43 is pivotally mounted therein. Second opposing end portion 45 of cover 27 is thereby adapted for substantially covering one of the recessed areas 31. By doing so, cover means 27 substantially covers the portion of wires 11 located within the recessed area. In FIGS. 6 and 7 one of the covers 27 is shown in the closed position while the opposing cover 27 is shown in the open position. Electrical wires 11 are removed from FIG. 6 for reasons of clarity. In FIG. 7, one wire 11 is shown positively secured within housing 23 by the closed cover 27.

First opposing end 43 of cover means 27 is provided with a pivot portion 47 which pivotally mounts within a corresponding recess 49 defined within contact receiving portion 33. Recess 49 is also illustrated in FIGS. 2 and 3 with the corresponding cover 27 removed for clarification. Although a recess 49 is defined by each of the contact receiving portions 33 of the invention, it is understood that first opposing end 43 of each cover 27 need only two pivot portions 47 to provide the described pivotal motion. As is further understood, several such pivot portions 47 can be provided on each of the covers 27, depending on the length of the cover member and corresponding body portion 29.

As stated, each recess 49 is defined within each of the contact receiving portions 33. Each contact receiving portion 33 in turn is defined by a pair of opposing upstanding first boss portions 51 (reference particularly FIGS. 3 and 7) a pair of opposing upstanding second boss portions 53, and a pair of opposing upstanding third boss portions 55. Each of the above boss portions are also adapted for aligning with various upstanding parts of first end 43 of cover 27 in a manner to be described. With reference to FIG. 3, extending portion 35 is shown as it extends below body portion 29 of housing 23. It is also shown that first boss portions 51 are positioned at the lowermost portion of body 29.

To assure alignment of tail portions 41 of each of the contacts 25 within connector 10, extending portion 35 includes a plurality of elongated rib members 57. Two opposing ribs 57 are provided for each tail 41 in the manner shown in FIG. 3. As illustrated, each tail portion aligns with the respective pair of ribs 57 and is adapted for slidably engaging said members. This positioning relationship assures a means whereby tail portions 41 will not be laterally displaced during positioning of connector 10 within PCB connector 17. To further assure this alignment, tail portion 41 includes a pair of extending retention arms 59 (shown in FIG. 5), each of which are adapted for providing an interference fit between the tail portion and the adjacent ribs 57. This relationship in turn is specifically designed to prevent outward displacement of the tail portions away from extending portion 35 during positioning of connector 10 in PCB connector 17.

With reference to FIGS. 4 and 6, a preferred embodiment for one of the cover means 27 is shown. Cover 27 is shown as comprising the first and second opposing end portions 43 and 45, respectively. First end 43 is also shown as having the aforementioned pivot portions 47. A total of five such members are illustrated as being spacedly positioned along end portion 43. Second end 45 preferably includes latching means 61 thereon, said means 61 comprising a pair of extending latch members 63 which are adapted for positively engaging body

portion 29 when the cover 27 is closed over recessed area 31.

Second end 45 also includes first alignment means 65 which assists in aligning cable 21 within connector 10. As shown in FIG. 1, each of the cover members 27 include first alignment means 65, each preferably in the form of two aligning tabs 67. When the covers 27 are closed on body portion 29, tabs 67 align with a corresponding second alignment means 69 located on body portion 29. As shown in FIG. 2, second alignment means 69 preferably comprises four aligning tabs 71 substantially similar to tabs 67 on covers 27. When the connector is in the closed position, the above aligning tabs align in such a manner that cable 21 may be positioned atop connector 10 in one of two ways. The cable can be positioned in the manner indicated in FIG. 1 or it can be positioned from an opposing direction.

Cover means 27 further includes a first strain relief means 73 for relieving tensile strain on wire 11 when the wire is positioned within contact 25. First relief means 73 preferably comprises an elongated upstanding member 75 which is adapted for engaging wire 11 to force the wire against body portion 29 of housing 23 when second end 45 of cover 27 covers recessed area 31. Attention is called to FIG. 7 where this relationship is fully shown. First strain relief means 73 may also include a second upstanding elongated member 75' which positively engages wire 11 in the same manner as that of member 75.

Body portion 29 of housing 23 also preferably includes a second means 77 for relieving tensile strain on wire 11. As illustrated in FIGS. 1 and 2, second strain relief means 77 comprises at least one rib member 79 having an open portion 81 on each side thereof. When incorporating a plurality of wires 11 within connector 10, two ribs 79 are preferably utilized. Strain relief is thus provided by each of these members when the wiring is wound thereabout in the circuitous manner shown in FIG. 1. Thus it can be seen that at least two strain relief means can be provided for wiring 11 when the wires are properly oriented within connector 10. The first strain relief 73 serves primarily to relieve tensile strain on the portion of the wire positioned in contacting portion 37 of contact 25 while second strain relief means 77 primarily serves to relieve tensile strain on cable 21. As shown however, relief means 77 also serves to relieve tensile strain on the portion of wire 11 within contacting portion 37 of the contact.

In FIG. 8 there is shown an alternate embodiment of a cover means for use with the present invention. As will be described, alternate cover 27' includes means for providing severance of wire 11 once the wire is initially positioned within contacting portion 37 of electrical contact 25. Severance of wire 11 is achieved when cover 27' is closed on housing 23 to cover recess 31. As further understood, cover 27' also provides complete positioning of wire 11 within contacting portion 37. During said closing, an actuating means 83, preferably in the form of a protruding boss member 84, positively engages wire 11 when the wire is first oriented within contacting portion 37 of contact 25. This first orientation is illustrated in FIG. 9. The pivotal closing of cover 27' thus causes boss 84 to force wire 11 downward onto a substantially V-shaped angular edge 85 provided on contacting portion 37. Angular edge 85 thus cuts an end segment 87 from wire 11.

In FIG. 8, alternate cover 27' is also shown as including pivot portions 47' and first strain relief means 73,

said components acting in the same manner as their counterparts on cover 27.

Thus it can be seen that the connector of the invention includes several important features which facilitate positioning and retention of electrical wiring therein. By use of pivoting cover members, the connector also provides for ease of repair and replacement of said wiring.

With reference to both FIGS. 5 and 5A, the preferred electrical contact of the invention is shown. As stated previously, contact 25 includes a contacting portion 37, a retention portion 39 substantially adjacent contacting portion 37, and a tail portion 41 adjacent retention portion 39. Contact 25, preferably of one-piece construction, is particularly adapted for electrically contacting an electrical wire 11 having a substantially round electrically conductive portion 89 and a portion of electrically insulative material 91 thereabout.

Contacting portion 37 includes a base portion 93 and first and second opposingly positioned and upstanding sides 95 and 97, respectively. First side 95 includes therein a slotted opening 99 having a substantially uniform width (indicated as a in FIG. 5A). Width a is equal to or less than the corresponding diameter for conductive portion 89 of wire 11. Thus, when wire 11 is positioned within slotted opening 99, insulative material 91 will be stripped therefrom and conductive portion 89 will electrically engage the sides of opening 99.

Slotted opening 99 is shown as being of a predetermined depth b within first side 95. Preferably, this depth extends approximately the full length of side 95 to assure a more positive seat of wire 11 within opening 99.

Second side 97 includes therein an opening 100 including the aforementioned substantially V-shaped angular edge portion 85, the purpose of said edge to sever an end segment of wire 11. In the preferred contact of the invention, the depth c of angular edge 85 is less than the corresponding depth b for opening 99. The illustrated comparative relationship between these depths assures a means whereby positive stripping of the wire's insulation material will occur after any undesired end segment of the wire has been removed.

To facilitate first orientation of wire 11 within contacting portion 37, slotted opening 99 is provided with an upper tapered portion 101. Tapered portion 101 initially retains wire 11 prior to the aforementioned severance procedure.

Although there has been shown (in FIG. 8) means for assisting in the severance and completed seating of wire 11, it is fully understood that other means are possible for accomplishing this operation. In the event that a cover is employed which does not include the unique actuating means 83 depicted in FIG. 8, a bladed tool member such as a screwdriver may be used to engage wire 11 and force it down onto edge 85 and into slotted opening 99.

In FIG. 5, contacting portion 37 is shown as being of a substantially closed loop configuration. This configuration is preferably rectangular in cross-section and includes a substantially flat member or portion 103 which interconnects sides 95 and 97. Within flat portion 103 is shown an elongated opening 105 which extends across portion 103 and interconnects the openings within sides 95 and 97. Thus, when wire 11 is first positioned within contacting portion 37, it is oriented within opening 105.

The preferred angle (d in FIG. 9) for edge 85 is approximately 45° with upstanding side 97. It is under-

stood, of course, that angle d can form almost any acute angle with side 97.

The retention portion 39 of contact 25 is shown as including at least two protruding tip members 107. Each of these members provides spring-like retention action to assist in retaining contacting portion 37 within an electrical component such as connector 10. In the particular embodiment of the invention as shown in FIG. 7, two grooves 109 are provided within the connector's contact receiving portion 33. Accordingly, each of the tip members 107 is adapted for being slidably oriented within one of these grooves to engage the walls thereof. Positioning of tips 107 within grooves 109 depresses the tips to effect a spring-action type retention between retention portion 39 and the walls of grooves 109.

Thus there has been shown and described an electrical connector and contact which provide several new features over prior art devices. The key features of the invention, as described, provide for facile placement and severance of electrical wiring within these components. Further, it has been shown and described that repair and replacement of this wiring has been facilitated. The connector of the invention is particularly adapted for use with a typical printed circuit board connector, thus providing a new usage for these devices.

While there has been shown and described what are at present considered the preferred embodiments of the invention, it will be obvious to those skilled in the art that various changes and modifications may be made therein without departing from the scope of the invention as defined by the appended claims.

What is claimed is:

1. An electrical connector for electrically interconnecting at least one electrical wire and at least one electrical contacting member positioned within an insulative member, said connector comprising:

an electrically insulative housing comprising a body portion including at least one recessed area therein 40 adapted for having said wire located therein and at least one contact receiving portion positioned relative to said recessed area, and an extending portion extending from said body portion;

at least one electrical contact comprising a contacting portion positioned within said contact receiving portion of said housing for electrically contacting said wire when said wire is positioned therein, a retention portion adjacent said contacting portion for retaining said contacting portion of said contact 50 within said contact receiving portion of said housing, and a tail portion adjacent said retention portion and adapted for electrically contacting said contacting member within said insulative member, said tail portion extending from said body portion 55 of said housing in an engaged relationship to said extending portion of said housing; and

at least one cover means comprising first and second opposing end portions, said first end portion pivotally mounted on said housing in the region substantially adjacent said contact receiving portion, said second end portion adapted for covering said recessed area of said housing, said second end portion including latching means for positively engaging said body portion of said insulative housing to latch 60 said second end portion to said housing;

characterized in that said cover means includes first strain relief means for relieving tensile strain on said

electrical wire when said wire is positioned within said contacting portion of said electrical contact.

2. The electrical connector according to claim 1 wherein said first strain relief means comprises at least one upstanding member on said cover means, said upstanding member adapted for engaging said wire to force said wire against said body portion of said housing when said second end portion of said cover means covers said recessed area of said housing.

3. The electrical connector according to claim 1 wherein said body portion of said insulative housing includes second strain relief means therein for relieving tensile strain on said electrical wire when said wire is positioned within said contacting portion of said electrical contact.

4. The electrical connector according to claim 1 wherein said second strain relief means comprises at least one rib member having an open portion on each side thereof, said rib member providing strain relief for said wire when said wire is wound about said rib member in a circuitous manner.

5. The electrical connector according to claim 1 further including wire severance means for severing said wire when said wire is positioned substantially within said contacting portion of said electrical contact.

6. The electrical connector according to claim 1 wherein said wire severance means comprises a substantially V-shaped angular edge portion on said contacting portion of said contact and actuating means on said first end portion of said cover means, said actuating means adapted for engaging said wire positioned substantially within said contacting portion of said contact to force said wire onto said angular edge portion during the pivotal movement of said cover means.

7. An electrical contact for electrically contacting an electrical wire having a substantially round conductive portion and an insulative portion about said conductive portion, said contact comprising:

a contacting portion including a base portion and first and second opposingly positioned and upstanding sides, said first side having a slotted opening therein of a substantially uniform width and a predetermined depth, said uniform width equal to or less than the diameter of said substantially round conductive portion of said wire,

a retention portion substantially adjacent said contacting portion; and

a tail portion substantially adjacent said retention portion; and

characterized in that the second side of the base portion of the contacting portion has an opening therein including a substantially V-shaped angular edge portion, the depth of said angular edge portion less than said predetermined depth of said slotted opening in said first side.

8. The electrical contact according to claim 7 wherein said contacting portion is of a substantially closed loop configuration.

9. The electrical contact according to claim 8 wherein said closed loop configuration is substantially rectangular in cross-section and includes a substantially flat portion interconnecting said first and second sides, said flat portion having an elongated opening extending there-across and interconnecting said openings within said first and second upstanding sides.

10. The electrical contact according to claim 7 wherein the angle of said V-shaped angular edge portion is about 45° with said second upstanding side.

11. The electrical contact according to claim 7 wherein said slotted opening within said first upstanding side extends substantially the full length of said upstanding side.

12. The electrical contact according to claim 7

wherein said retention portion includes at least two protruding tip members.

13. The electrical contact according to claim 7 wherein said contact is of one-piece construction.
